CLAIM

The ornamental design for an electric coffee grinder, as shown and described.

DESCRIPTION

FIG. 1 is a front, top perspective view of an electric coffee grinder, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof; and,

FIG. 9 is another perspective view of the electric coffee grinder, shown in an alternate configuration.

The broken lines in the figures illustrate portions of the electric coffee grinder that form no part of the claimed design.
